UNITED STATES PATENT OFFICE

EDMUND C. MORGAN, OF CHICAGO, ILLINOIS; OLIVE EUGENE MORGAN EXECUTRIX
OF SAID EDMUND C. MORGAN, DECEASED

APPARATUS FOR MINING COAL

Original application filed July 5, 1913, Serial No. 777,436. Divided and this application filed February 8, 1916. Serial No. 76,911.

My invention relates to improvements in apparatus for mining coal and other materials, and is a division of my co-pending application Serial No. 777,436, filed July 5, 1913, for an improvement in apparatus for mining coal.

One of the objects of my invention is to provide an improved and simplified construction for mining coal and other materials, arranged so as to be efficient, reliable and rapid in operation particularly when it is desired to remove comparatively large blocks of material from a mine wall.

Other objects of my invention will appear hereinafter, the novel combinations of elements and novel features of the invention being set forth in the appended claims.

Referring to the accompanying drawings, Fig. 1 is an elevation of an improved mining machine;

Fig. 2 is a plan view of Fig. 1;

Fig. 2^a is a sectional elevation on line 2^a—2^a of Fig. 1;

Fig. 3 is a vertical sectional view substantially on the line 3—3 of Fig. 2, illustrating the adaptability of the parts to the various positions of the kerf-cutting devices;

Fig. 4 is a detail view of a rolling mill joint used between the cutter heads and the driving mechanism therefor;

Figs. 5 and 6 are detail views of the parts by which the cutting mechanism may be removably attached to the driving mechanism;

Fig. 7 is an enlarged vertical view substantially on the line 7 of Fig. 2, this view being partly in section and illustrating details of the balancing supports for the kerf-cutting devices;

Fig. 8 is a sectional view substantially on the line 8—8 of Fig. 1;

Fig. 9 is a plan view of loop chain cutters connected to horizontal kerf cutters;

Fig. 10 is an elevation of the construction shown in Fig. 9;

Fig. 10^a is a detail sectional view on the line 10^a—10^a of Fig. 10, looking in the direction of the arrows;

Fig. 11 is a detail transverse sectional view on the line 11—11 of Fig. 10, looking in the direction of the arrows;

Fig. 12 is a view in diagram illustrating a vein or seam of coal in its native bed in the mine, into which a plurality of kerfs have been cut in accordance with the principle of operation of my improved mining machine disclosed herein; Fig. 13 is an elevation of Fig. 12;

Fig. 14 is a diagrammatic sectional view of the vertical kerfs, on the line 14—14 of Fig. 13;

Fig. 15 is also a diagrammatic sectional view of Fig. 13 but taken on the line 15—15, looking in the direction of the arrow.

In the mining of coal, it is particularly desirable to remove the coal from the mine wall in large, regular and uniform blocks, so that not only may they be conveniently removed from the mine and packed for transportation but the efficiency of the coal in large blocks will be retained much better than if broken into comparatively small particles. In the drawings, particularly in Figs. 12 to 15 inclusive, I have diagrammatically illustrated an improved method of mining coal in large blocks, which can be carried out by the improved mining machine disclosed herein.

Referring to Figs. 12 to 15 inclusive, A indicates a vein or seam of coal which may be representative of any vein or seam from which coal is to be mined. These views show the operations in the progress of running an entry into the vein.

A plurality of kerfs spaced apart, as shown, are cut into the vein or seam a substantial distance horizontally, in accordance with the requirements and conditions of the particular vein which is to be mined. As shown in the drawings, these kerfs lie in planes disposed at angles with respect to each other so that the coal will be divided up into a plurality of blocks of convenient and practical size. The horizontal kerfs B lie preferably in substantially horizontal planes with respect to the pitch or inclination of the vein, and preferably extend from one side of the mine chamber to the other. These kerfs also extend into the vein longitudinally whatever distance is found to be practicable under the particular conditions. In the diagram in Figs. 12 and 13, the horizontal planes in which these kerfs B are

cut are preferably parallel and arranged one above the other, and there may be as many of such kerfs as the conditions require, preferably at least three. In the diagrams 5 designated Figs. 12 to 15 inclusive, I have illustrated three such horizontal kerfs, one along the roof of the mine chamber, one along the floor of the mine, and one intermediate the upper and lower kerfs and preferably equally 10 spaced therefrom. The thickness of the vein and the size of the blocks to be removed will determine the number of such kerfs to be made.

The vertical kerfs C preferably lie in substantially vertical planes and approximately at right angles to the horizontal kerfs. Furthermore, such vertical kerfs are spaced apart at intervals and across the width of the room. These vertical kerfs may extend into the vein any desired distance, but the best results are obtained by extending them slightly beyond the inner edges of the horizontal kerfs, as shown in Figs. 14 and 15 and illustrated in dotted lines in Figs. 12 and 13. While the vertical kerfs C may be cut so as to intersect the horizontal kerfs, and thereby completely sever the blocks of coal from the mine wall except at the rear end thereof, I find it desirable to leave small uncut portions C' adjacent the horizontal kerfs, as shown in Fig. 14, particularly when the vertical kerfs are cut first, and a kerf-cutting or mining machine is used in making all the kerfs. These uncut portions C', although relatively thin, serve to hold the blocks against lateral displacement when a strain comes upon them during the cutting of the horizontal kerfs. That is to say, as the cutting of the horizontal kerfs progresses from one side of the room to the other, strains or pressure exerted by the cutting mechanism along the line of the horizontal kerfs will not operate to break loose the blocks and move them laterally even though the vertical kerfs C have already been cut, for the reason that the uncut portions C' serve to hold the blocks in position against this lateral pressure. The uncut portions C' do not resist to any appreciable extent the breaking loose of the blocks of coal and the movement thereof in a substantially vertical direction when the blocks drop or break loose by reason of their own weight, or when, as may be necessary in some cases, a slight force is used to dislodge them.

In addition to the vertical kerfs C, I also cut a continuous vertical kerf D in the rear of the horizontal kerfs B and the vertical kerfs C. The number of these vertical kerfs D depends upon the number of horizontal kerfs B. In the drawings, I have shown three horizontal kerfs B as previously described, and in consequence I cut only one kerf D between the upper and lower horizontal kerfs B. The rear vertical kerf D lies in a general plane

which is substantially transverse to the planes of both the horizontal kerfs B and the vertical kerfs C. In the drawings, the rear vertical kerf D is shown intersecting the intermediate horizontal kerf B and also all of the vertical kerfs C. Preferably the rear vertical kerf D does not extend either upwardly or downwardly a sufficient distance to intersect the upper and lower horizontal kerfs B but stops short of these last-mentioned kerfs. This leaves the uncut portions D' along the rear ends of the blocks of coal, and the purpose of the kerf D is simply to weaken the portions or ends of the blocks or slabs of coal which are attached to the body of the vein or mine wall, so that the blocks may be readily broken loose from the mine wall, either by gravity which will cause them to drop downwardly, or by reason of a slight additional force, if such additional force is found to be necessary.

In Fig. 12 I have shown the end portions D² of the kerf D and the end portions of the horizontal kerfs B as being cut upon a curve or arc; although this is preferable, it is not necessary, as the said end portions may be given any configuration desired. The arc-shaped ends shown, however, are of advantage for certain types of mining machine, such as disclosed herein are used, for the reason that it enables the cutting mechanism to start into the vein at the front ends or front portions of the wall of material, and these arc-shaped end portions also serve to determine the width of the room and to form the side walls thereof.

In mining coal in the manner illustrated in Figs. 12 to 15 inclusive, I prefer to cut the vertical kerfs C first and then cut the horizontal kerfs B and the vertical kerfs D by means of the apparatus herein disclosed. The horizontal kerfs and the vertical kerfs D may be cut simultaneously. In cutting the kerfs B and D, I prefer to start the cutting mechanism into the mine wall substantially at the point D³ at one side of the room, and carry on the cutting operation gradually from this point across the mine wall to the other side of the mine chamber. As the cutting of the kerfs B and D progresses across the mine wall, there is a tendency for the blocks thus formed to drop of their own weight, but to prevent these blocks from dropping, and binding the cutting mechanism, I support the blocks in their positions until at last the cutting mechanism has passed each block. The blocks may be supported in any desired manner and the supports left in place, if desired, until all of the blocks are bounded by kerfs; or the supports may be removed as soon as the cutting mechanism passes the vertical kerfs C and the blocks allowed to drop successively.

In the machine illustrated in the draw- 130

ings and described hereinafter, I provide a support for the blocks which trails along in the kerfs immediately following the cutting mechanism and temporarily supports the blocks from which the kerfs have been cut, this supporting mechanism gradually moving from under the blocks and allowing them to drop if the condition of the coal is such that they will break loose of their own weight, or at least leaving the blocks in such condition that they may be broken loose by the application of a comparatively slight force.

It should also be understood that if desired the machine hereinafter disclosed may first cut the horizontal kerfs B and the rear vertical kerfs D, after which the vertical kerfs C could be cut by means of any well known vertical kerf-cutting machine and the blocks of coal thus dislodged from the mine wall by gravity loaded on mine cars by means of a loading machine.

Referring now to the views of the drawings which illustrate my improved mining machine, it will be seen that the mining machine proper is mounted upon a suitable truck E, having wheels 1 so that it may travel along suitable rails or tracks 2 laid in the mine chamber. These wheels 1 are mounted upon axles having journals rotating in bearings of the truck frame E, each axle carrying a bevel gear 4. A shaft 5 extends longitudinally of the truck and carries at its ends the bevel gears 6, which mesh with the bevel gears 4 and through the medium of which and the shaft 5 the truck may be propelled along the track. One of the gears 4 is disposed at one side of the shaft 5 and the other bevel gear 4 is disposed at the opposite side of the shaft 5, so that the latter will rotate both sets of wheels 1 in the same direction, and power will thus be applied to all of the wheels of the truck, so that the tractive effort will be well distributed. In order to lock the truck to the track and at the same time permit the truck to travel along the track, I provide a set of angularly disposed flanged wheels or rollers 13, the flanges of which, as shown in Fig. 1, engage the under side of the ball of the rails 2 and thereby prevent the block from being tilted or raised relatively to the track by any strains or undue loads which may come upon the mining machine and which might have a tendency to overbalance it. These locking wheels or rollers 13 are mounted at the lower ends of the depending arms 14, which arms are rotatably mounted upon the short shafts 15 outstanding from the frame of the truck so that the locking wheels may be swung inwardly, away from the track rails, to permit raising of the truck from the track, in the event that it is desired to do so on such an occasion as when the machine is to be taken out of the mine or the track relaid in other parts of the mine.

The bearing portions of these rotary arms 14 have gear teeth 16 which mesh with and are driven by worms 17, the latter being mounted upon the ends of the short shafts 18, journaled in bearings 19 on the truck frame, and carrying hand wheels 20 by which they may be operated. This construction permits the locking wheels to be readily thrown out of engagement with the track and at the same time the worm gearing serves to lock the arms in any positions to which they are rotated.

The truck frame E is shown in the form of a flat platform which has an upstanding annular rim or flange 21 of comparatively large diameter. The various parts of the driving and cutting mechanism are primarily supported upon a broad flat platform 25, which has an underhung parallel or sub-platform 26 rigidly fastened thereto, as shown in Fig. 1. This sub-platform 26 has a depending annular flange or rim 27 telescoping into the upstanding circular flange 21 of the truck. The flange 27 is of such diameter that it telescopes within the flange 21, and the two together in conjunction with the platform 25 constitute a turntable, the two flanges 21 and 27 being relatively rotatable.

A motor M is mounted upon the platform 25 at one side thereof so as to assist in balancing the machine against the weight of the cutting mechanism, which is in general disposed at the opposite side of the platform 25. The motor shaft, as shown in Fig. 2, carries a pinion 28 which drives a large gear 28^a, which is mounted upon a shaft 29 supported in bearing standards 30 on the platform 25. The shaft 29 carries the pinion 31, which is connected to a train of gears 32 and 33. The shaft 29 may be said to constitute the main shaft of the machine, because from it the various mechanisms are driven. The gears 28 and 28^a are of such ratio as to properly reduce the speed of the motor. The gear 33 is comparatively large in diameter and is mounted upon a countershaft 34, which is journaled in bearing standards 35 rising from the platform 25. The intermediate gear 32 is mounted upon a shaft which is suitably journaled in a bearing 36 mounted upon platform 25, and is interposed between the gears 31 and 33 for the purpose of securing the proper direction of rotation of the countershaft which is mounted in the bearing 35. This countershaft 34 carries loosely two bevel gears 37, which mesh with a similar bevel gear 38 interposed between them. The bevel gears 37 may be connected with or disconnected from the shaft 34 by means of an intermediate two-way clutch member 39, so that the shaft 34 may be arranged to drive either of these gears. The clutch mechanism may be of any suitable kind for the purpose. In the drawings I have shown the clutch member 39 as being a longitudinally slid able sleeve splined

on the shaft 34 to rotate therewith, and being adapted to be shifted longitudinally in either direction by means of a manually operated lever 40. Thus, by shifting the clutch member 39 into engagement with either one of the gears 37, the latter may be connected with the shaft 34 to be driven thereby. The gears 37 and the clutch member 39 have corresponding teeth for interlocking the two together.

10 The purpose of this arrangement is to permit the shaft 42 (Fig. 1), upon which the gear 38 is mounted, to be driven in either direction. The shaft 42 is mounted in the bearing 43 (Fig. 2) rising from the platform 25, and carries a bevel gear 44 at its other end which meshes with a similar bevel gear 45, the latter being mounted upon a vertical shaft 46 journaled in a bearing outstanding from the platform 25. The shaft 46 projects below the platform 25 (Fig. 1), and carries at its lower end a pinion 47 which meshes with and drives the large spur gear 48 disposed between the main platform 25 and the sub-platform 26. The large gear 48 is mounted upon the upper end of a vertical shaft which is journaled at its upper end portion in the sub-platform 26.

15 The shaft 49, as shown in Fig. 2^a, is journaled in the sub-platform 26 and extends vertically downward through the center of the flanges 21 and 27. Below its upper bearing the shaft 49 is perfectly square in cross-section and is adapted to slide vertically within a correspondingly square-holed bushing 50. This bushing is rotatably journaled 20 in the rotary bushing E², so that a sliding bearing is thus formed for the lower end portion of the shaft 49, permitting the shaft to adapt itself to the various positions to which the platforms 25 and 26 are raised or lowered with respect to the truck. The shaft 49, however, on account of its being squared with respect to the bushing 50, will drive the latter at any position in which the shaft is adjusted. The bushing 50 carries a bevel gear 35 51 on its lower end, which bevel gear meshes with and drives a similar gear 52 on the shaft 5 beneath the truck, which shaft transmits power, as before described, through the bevel gears 4 and 6 to the wheels of the truck.

25 45 By this construction it will be seen that the power of the motor is transmitted through the various shaft clutches of the gears above described to the wheels 1 of the truck, to propel the latter along the track, the direction of movement of the truck being controlled by the clutch member 39 (Fig. 2), which is positioned intermediate the bevel gears 37 on the counter-shaft 34. It will be noted, however, that since the large horizontal gear 48 is carried, generally speaking, by the truck, and the pinion 47 which meshes with this large gear is carried, generally speaking, by the rotary platform or turntable 25, there is a tendency for the pinion 47 to "walk around" the 30 50 large gear 48 instead of actually rotating or

driving the large gear, provided that the resistance offered by the wheels to the movement of the truck along the track is greater than that which is offered by the platform 25 to the rotary movement about its axis. In other words, if the truck offers greater resistance to being propelled along the track than the platform 25 does to being rotated, the pinion 47 will travel around the large gear 48 and thereby rotate the platform, rather than actually rotate the large gear itself to propel the truck along the track. This planetary gear arrangement is used in combination with brake mechanism applied to the truck wheels, which in a sense locks the truck to the track. When the brakes are applied, the large gear 48 is practically locked against rotation, and in consequence when the pinion 47 is driven it will travel around the periphery of the large gear 48 and the platform will thereby be given a rotary movement. This condition of the mechanism also holds good in the other way; that is to say, if the resistance offered by the platform or turntable to being rotated is greater than offered by the truck to being propelled along the track, the result will be that the large gear 48 will be actually rotated by the pinion 47, and the resultant power will be applied to propel the truck along the track. In order, therefore, to afford resistance to the rotary movement of the platform, I provide means by which the platform may be positively locked against rotation upon the truck frame.

In Fig. 1 is shown a boss 53 projecting from one side of the cylindrical truck flange 21. This boss 53 is screw-threaded and carries a pin 54 which may be screwed into or out of any one of the series of elongated openings 55 distributed around the inner cylindrical flange 27. This pin 54 is provided with a hand wheel 56 at its outer end, by which it may be operated. This pin in conjunction with the holes or openings 55 serves to lock the two flanges against relative rotation, and thus lock the platform 25 against rotation relatively to the truck. The pin 54 may be withdrawn from whatever opening 55 it happens to be in, by turning the hand wheel 56 when it is desired to rotate the platform or turntable.

Upstanding from the platform or turntable 25 is a pair of bearings 60, in which is journaled a shaft 61, as shown in Fig. 2. This shaft carries and is driven by a gear 62, which meshes with the gear 63 on the counter shaft 34. The rope drum 64 is rotatably mounted upon the shaft 61 and is adapted to be connected with or disconnected from the shaft by means of a sliding clutch member 65 having teeth 66 arranged to interlock with corresponding teeth on the drum 64. The clutch member 65 may be readily shifted by means of a hand lever 67. The rope drum 64 may be

used independently of the previously described truck propelling mechanism, or it may be used in conjunction therewith when the resistance offered to the cutting mechanism is too great to be overcome by the tractive effort of the truck wheels alone. The manner in which this winding drum 64 may be used is to fasten thereto and wind thereon a cable 68, anchored at a point 69 in the mine 10 distant from the mining machine, and then actuating the drum by throwing in the clutch 65. The cable may be anchored at any point in the mine, and in conjunction with the winding drum 64 may be used to pull the machine 15 along the track whether the said track be laid in curves or in a straight line, as is the usual practice in mining operations.

The platform 25 carries at one side thereof a rigid upstanding casing or member 70, as 20 shown in Fig. 1, which forms a guideway or supporting member for two vertically reciprocable or sliding members 71, 72, which are bifurcated as shown in Fig. 7, so as to leave an open space 73 between their respective bifurcations. These reciprocable members 71, 25 72 support the upper and lower kerf cutters at their upper and lower ends respectively, and by reason of their vertical slidability the kerf cutters may be raised and lowered to vary the 30 height of the mine chamber.

In order to reduce to a minimum the power required for reciprocating the members 71 and 72 together with the kerf cutters carried thereby, I arrange the mechanism so that the 35 weight of the upper member 71 together with the kerf cutter connected thereto will assist in raising the lower member 72 together with the kerf cutter carried thereby. One of the bifurcations of each of the members 71 and 40 72 is provided with gear teeth 74 and 75 to form racks, the two sets of teeth or racks being disposed on opposite sides of the opening 73, as clearly shown in Figs. 7 and 8. Between the two racks and meshing therewith 45 is a broad-faced pinion or gear 76, the hub portions of which are rotatably journaled in the upstanding guide member 70 as shown in Fig. 8, so that these journals will take the entire weight of the cutting mechanisms. At 50 one end, the hub member 77 of the pinion 76 is provided with a worm gear 79 which is driven by a worm 78, the latter being mounted upon a shaft 80 which is journaled in a bracket 81 on the guideway member 70 and 55 has at its other end a hand wheel 82 for the convenient operation thereof. It will thus be seen that by rotating the hand wheel 82, the pinion 76 may be rotated and the members 71 and 72 reciprocated vertically relatively 60 to each other and to the pinion 76. It will be particularly noted also that the weight of the member 71 and the cutting mechanism mounted thereon, in moving downward, will assist in the rotating of the pinion 76 and 65 cause the pinion to exert, through the rack

75, a lifting action upon the member 72, or vice versa. When the cutting mechanisms are to be adjusted farther apart, the weight of the member 72 and its cutting mechanism, in moving downward, will assist in rotating the pinion through the medium of the rack 75 and the pinion will, in turn, operate upon the rack 74 to assist in raising the member 71 and its cutting mechanism. Thus it will be seen that the weights of the members 71 and 72 70 and their cutting mechanisms balance each other, and very little power will be required to rotate the pinion to adjust the cutting mechanisms any desired distance apart. It will be noted also that the worm gears 78 and 79 serve as an automatic locking mechanism to hold the parts in any position to which they are adjusted. The pinion 76 and its hub 77 are hollow and form a bearing for the main shaft 29 which extends through its brackets 80 beyond the hub and carries at its outer end a bevel pinion 83. It will be noted, however, that the shaft 29 is relieved of the weight of the cutting mechanisms, since this weight is taken up by the bearings for the hub 77 in 85 the guideway member 70. The pinion 83 meshes with and drives a large horizontally disposed bevel gear 84 (Figs. 1, 2, 3 and 8), which gear 84 is carried by and preferably formed integrally with an elongated sleeve 90 95 85, and it is through this mechanism that the driving power is transmitted to the cutting mechanisms. The sleeve 85 is journaled in the bearings 86 which are formed in an extension 87 of the main platform 25, as shown in Figs. 1, 2 and 3. The sleeve 85 carries a removable collar 88 at its lower end, which normally prevents it from being shifted upwardly out of its bearings, and the gear 84 forms a collar 100 for this same purpose at the upper end of the 105 sleeve.

The sleeve 85 is adapted to drive the two shafts 89 and is hollowed for its entire length so as to form rolling mill joints for the ends 90 of the shaft 89, as clearly shown in Fig. 3. The rolling mill joints between the shafts 89 and the sleeve 85 permit universal movements of said shafts to take care of any inequalities which would be likely to bind the shafts in the event that they were rigidly mounted in the sleeve 85, and they also permit the shafts to move vertically in the sleeve 85 to accommodate the raising and lowering of the upper and lower kerf cutters. These rolling mill joints also permit the upper and lower kerf cutters to be slightly inclined upwardly or downwardly, as will be later explained. In the machine shown in the drawings, I have provided three sets of kerf cutters, an upper, a lower and an intermediate 110 kerf cutter. These kerf cutters are in the form of flat elongated frames, comparatively thin, and arranged to cut relatively thin kerfs. Each kerf cutter has an elongated flat frame around the periphery of which the 115 120 125 130

cutting chain travels. The frames of the kerf cutters each comprise two main parts or members 95 and 96, as shown in Figs. 1 and 2. The member 96, as shown in Fig. 2, is provided with a slot into which fits a block 98 which has two threaded bars 99 extending longitudinally of the slot in opposite directions. These threaded bars extend through end portions of the tail pieces 97, and each carries at its outer end a nut 101. This mechanism forms a convenient and simple means by which the frame members of the cutting mechanism may be adjusted relatively to each other to tighten or loosen the chain cutters. Each of the central blocks 98 has journaled therein a shaft 102, to the upper end of which is keyed a sprocket wheel 103 around which the cutter chain extends and by which the latter is driven. The shafts 102 are carried upon cup-shaped members 104, as shown in Fig. 3. These members are hollow and arranged to form rolling mill joints in connection with the other ends 105 and 90 of the shafts 89, so that there are universal driving connections between the shafts 89 and the shafts 102. The cup-shaped members 104 are journaled in members 106 extending from the frame members 96. The latter are supported in cup-shaped members 107, and the connections between the members 106 and 107 are preferably in the form of bayonet joints, so that the upper and lower kerf cutters may be bodily removed from their supports in the event that it is desired to replace them or remove any of their parts. These bayonet joints, as shown in Figs. 3, 4, 5 and 6, are formed by providing the cup-shaped members 106 with laterally extending segmental flanges 108, which are adapted to engage in the undercut grooves 109 in the cup-shaped supports 107, the rims of the cup-shaped supports 107 being provided with cutaway portions or notches 110 to permit the insertion or withdrawal of the flanges 108. It will thus be seen that by entering the flanges 108 in the notches 110 and rotating the cup-shaped member 106 a portion of a turn, the cutting mechanism may be removably attached to the supports 107. The rims of the cup-shaped supports 107 have cams 111, as shown particularly at the lower end of Fig. 3. These cams 111 are located adjacent the notches 110 and are adapted to act upon the segmental flanges 108 to force the two members tightly together. The direction of rotation necessary to fasten the kerf cutters in place by these bayonet joints is opposite to that in which they rotate with the platform 25, so that the cutting operations will act to tightly set the cutting mechanisms in position on their supports.

It is desirable in a machine of this character that the cutting mechanisms be capable of being inclined slightly with respect to

their supports, so that they may be accurately adjusted, and to this end I have mounted the supporting members 107 upon the ends of the levers or arms 112, which are pivoted at 113 in extensions 114 of the vertically reciprocable members 71, 72, and the other ends of the levers or arms 112 are formed as segmental gears 115 which mesh with the worms 116. (See Figs. 1 and 7). The latter are mounted upon shafts in the ends of the members 71, 72, and these shafts are provided with hand wheels 117 by the rotation of which the arms 112 may be rocked about their pivots to vary the angular positions of the cutting mechanisms. The mechanism for adjusting the inclination of the lowermost kerf cutters differs from that for the uppermost kerf cutter only in the fact that the lever 112 is formed as a bell crank lever, so that the hand wheel 117 and the worm which it drives may be entirely clear from the floor of the mine and thus not interfere with the operation of the lowermost kerf cutter.

The cutting chains need no particular description except to say that they travel around the periphery of the frame member 95 and are provided with side links 118 to guide them on their frame and prevent the chains from becoming displaced. Each chain has a series of cutters or cutting tools 119 at spaced intervals. The intermediate kerf cutter is similar to the upper and lower kerf cutters except that it is not attached to its support by a bayonet joint. It has, however, means similar to that of the upper and lower kerf cutters for tightening and loosening the chain, and the description thereof need not be repeated. Its parts 96' and 97', as shown in Fig. 3, are wider than the corresponding parts of the upper and lower kerf cutters, so as to allow room for the driving sleeve 85. This intermediate kerf cutter also is not intended to be inclined or adjusted at different angles, as is the case of the other kerf cutters.

So far I have described only the cutting mechanism for cutting horizontal kerfs, which mechanism is described and claimed in my co-pending application Serial No. 777,436, filed July 5, 1913, for an improvement in apparatus for mining coal. The rolling mill joints for transmitting power to upper and lower kerf cutters I have shown described and claimed in my co-pending application Serial No. 764,487, filed April 30, 1913, for an improvement in mining machines. I will now describe the cutting mechanism which I wish to cover by the claims hereto appended both separately and in combination with the horizontal kerf cutting mechanism above described.

Where the rear vertical kerfs are of such a character that they are not intended to reach all the way to the upper and lower horizontal kerfs to completely sever the blocks of coal at their rear ends, I utilize a cutter wheel such

as that indicated at 140 in Figs. 1 and 2, but where the rear vertical kerf D is to be made wide or high enough to intersect the upper and lower horizontal kerfs and completely sever the blocks from the vein or from the mine wall, the structure shown in Figs. 9 and 10 is preferably for the reason that in the latter case a cutter wheel 140 of sufficiently large diameter to completely sever the rear ends of the blocks of coal would be too cumbersome to handle, especially when the curves D² (Fig. 12) at the ends of the kerf are to be made. The cutter wheel 140 is mounted in a suitable frame, as shown in Figs. 1 and 2, and is operated by the gear 33 which is mounted on the shaft 34. Provision may be made for oscillating the vertical cutter 140, but since the details of such construction are disclosed and claimed in my aforesaid co-pending application, Serial No. 777,436, a brief mention thereof here is sufficient.

The conditions and grades of coal vary in different mines. Coal in some mines is more likely to break loose of its own weight than in other mines. Consequently, in operating a machine of the character herein disclosed in some grades of coal the latter is likely to drop immediately behind the cutters, and perhaps tend to bind the cutting mechanism.

As a protection therefor, I provide an additional support which trails immediately behind the vertical cutter 140 and the lower horizontal cutting mechanism, as shown in Fig. 1. This support is preferably constructed as a lever which is suitably pivoted at 170 upon a bearing upstanding from the platform extension 87. The flat plate 171 is of sufficient length to extend almost to the ends of the kerf cutters, and is preferably in the form shown in Fig. 2, and is preferably slightly thinner than the thickness of the kerf cutter frame. This supporting plate is positioned to follow immediately behind the horizontal kerf cutters and to thereby support the coal above the same immediately after the kerf cutters have passed. In order that this supporting plate may be constantly urged upwardly and may yield to the inequalities of the kerfs and at the same time be sufficiently rigid to support the coal above it, the aforesaid lever has a short arm 172 upon which a stiff spiral spring 173 passes, thereby tending to raise the plate 171 upwardly. This spring 173 is confined between the ends of the lever arm 172 and the head 174 (Fig. 1) of a vertical bolt 175. This bolt passes through a lug 176 outstanding from the platform extension 87, and carries a nut 177 at its lower end by which the tension of the spring may be regulated as desired. The supporting device which is associated with the intermediate cutting mechanism is mounted upon the platform extension 87 and is positioned immediately behind the casing 143, which carries the vertical cutter 140. The lower support-

ing device associated with the lower horizontal kerf cutter, is identical in all respects to the one above described, and the description thereof need not be repeated except to say that it is mounted upon the member 96¹ of the kerf cutter frame. It may be desirable, under some conditions, to cut the vertical kerfs D all the way to the upper and lower horizontal kerfs, so as to completely sever or separate the blocks of coal from the body of the vein, and in Figs. 9 and 10 I have illustrated the mechanism embodying my invention for cutting the rear vertical kerfs D to completely sever the blocks of coal from the mine wall. I have illustrated, and will describe, this mechanism as operating in conjunction with the above described horizontal kerf cutters to completely sever the blocks on all sides, but it will be observed that this additional mechanism is of such construction that it may be used by itself to cut, not only the rear vertical kerf D, but also the horizontal kerfs all in the same operation. Although it is preferable to use both the horizontal kerf cutting mechanisms and also the loop chain cutters operating in vertical planes as hereinafter described, particularly when exceptionally hard material is to be cut from a mine wall, it should be understood that the horizontal kerf cutters may be omitted and the loop chain cutters, either one or both, used alone for producing the horizontal kerfs spaced apart as well as the vertical kerf connecting the rear ends of the horizontal kerfs.

Referring to Figs. 9 and 10, it will be observed that the horizontal kerf cutters are in general the same as those above described so far as their construction, operation and adjustments are concerned. Some of the details have been slightly modified so that the machine may be adapted to the mounting of the loop chain cutting mechanism. For instance, it will be noted that the upper and lower horizontal kerf cutters are mounted directly upon the lateral extensions 114 of the vertically reciprocating members 71 and 72, instead of being mounted upon the pivot arms 112 for adjustment. The hand wheel 82 and the parts which it operates to raise and lower the upper and lower horizontal kerf cutters is disposed, as shown in Fig. 9, upon the other side of the guideway 70, but its operation is substantially the same.

The main shaft 29, shown in Fig. 2, carries a large bevel pinion 200, as shown in Fig. 9. This pinion meshes with the bevel gear 201 mounted upon a transverse countershaft 202 which is journaled in bearings 203, two of which are mounted at intermediate portions of the large massive arms 204, which incline backwardly from the platform. The countershaft 202 carries a pinion 205 at its outer end, which through the medium of the gears 206, 207 and 208 and the short shaft 209, drives the countershaft 34, from which shaft, as

above described, the various propelling movements of the truck and the rotary movements of the platform are accomplished in the same manner. It should be observed that the shaft 209 is mounted in the bearing 300, which is supported at the upper end of the standard 301 mounted on the platform 25, as shown in Figs. 9 and 10.

The platform 25 supports two large rectangular loop-shaped frames designated in general U and L respectively, around the peripheries of which cutting chains 210 and 211 operate. These frames lie in substantially vertical planes, but the plane of the lower frame is preferably in advance of the plane of the upper frame in the direction of movement of the loop chain cutters. The lower reach or length of the upper frame and the upper reach or length of the lower frame are coincident with each other in a horizontal plane, as shown in Fig. 10, so that they will both enter and move in the intermediate horizontal kerf which has already been cut by the intermediate kerf cutter or which may be cut by the chain 211 when the horizontal kerf cutters are omitted. The upper horizontal dimension or reach of the upper frame and the lower horizontal dimension or reach of the lower frame are coincident with the upper and lower horizontal kerf cutters respectively, so that they may travel or move in the upper or lower horizontal kerfs cut by such horizontal kerf cutters or in the upper and lower horizontal kerfs made by the chains 210 and 211 where the uppermost and lowermost horizontal kerf cutters are omitted.

The upper frame U is provided with an extension or arm 212 which forms a horizontal guideway for a horizontal extension 216 integral with the intermediate arm 204, and the relatively sliding parts 212 and 216 support the frame U in such a manner that it may be shifted bodily horizontally to properly adjust it in this direction. The lower frame L is also equipped with a similar extension 214, which forms a similar guideway for the horizontal extension 213 which is integral with the platform 25 and the sub-platform 26, as shown in Fig. 10. These constructions permit the frames U and L to be bodily adjusted horizontally, and in order that this adjustment may be conveniently accomplished it will be seen that the guideway constructions 212 and 214 have slots or openings 217 in their faces and also outstanding lugs 218 at their outer ends. The horizontal extensions 213 and 216 have outstanding lugs 219 which move in the openings 217. The lugs 219 have openings through which adjusting bolts 220 extend, and these bolts carry nuts 221 on opposite sides of the lugs 218 and nuts 222 on opposite sides of the lugs 219, so that by manipulating the said nuts the frames U and L may be adjusted horizontally and secured firmly in their adjusted positions. The frames U

and L are preferably made each in two sections, so that they may be readily contracted or expanded in a vertical direction to properly align them with respect to the kerfs of the horizontal kerf cutters. The inner vertical dimensions or reaches 225 of one of the sections of each frame are formed as bearings which are adapted to telescope with or slide vertically in the vertical guides 226 of the other sections of each frame, as shown in Figs. 9 and 10, and the vertical guides 226 are provided with slots or openings 227 which accommodate lugs 228 movable therein and mounted upon the flat vertical bars 225. The vertical guides 226 have corresponding lugs 229 which carry adjusting bolts 230 and adjusting nuts 231, which are similar to the bolts and nuts previously described for obtaining the horizontal adjustment of the frames. The outer vertical dimensions or vertical reaches 233 and 234 respectively of the sections of the two frames also telescope with each other, as clearly shown in Fig. 11, which is a section on the line 14^a, 14^a of Fig. 10. No adjusting parts are required at the outer ends or reaches of the frames, since the adjusting bolts 230 and nuts 231 at the inner ends of the frames are sufficient, as shown in Fig. 10.

The upper, lower and outer end reaches or sides of the frames U and L have grooves formed therein for guiding the cutting chains 210 and 211. The corners of the frames and the grooves are preferably rounded, as shown in Fig. 10, so that the chains will travel freely. The chains may be guided, as shown in Fig. 11, and constructed of side links 235 and intermediate or center links 236 suitably connected together by hinges 237. It will be noted, however, that the central links 236 have lugs 236' outstanding laterally therefrom and preferably formed integrally therewith. These lugs project beyond the faces of the side links 235 and are provided with suitable sockets into which the tools 238 will be inserted, the tools being held in such sockets by means of set screws or by any other suitable means. Thus it will be seen that although the chains may travel in the usual manner of operating chains of this character, the cutting tools 238 project laterally from the grooves in the frames in which said chains run. In other words, the cutting portions or parts 238 of the chains are disposed laterally with respect to the vertical plane of the entire loop chain both in the frame U and in the frame L, and when these frames are swung or moved in a horizontal direction they will cut horizontal kerfs when the horizontal kerf cutters above described are omitted, or they will move freely in the horizontal kerfs if such kerfs have already been cut by the above described horizontal kerf cutters shown in Figs. 1 and 2.

Although it is preferable to use the loop

chain cutters mounted on the frames U and L in combination with the above described horizontal kerf cutters so as to minimize the strains on the frames U and L, it should be understood that such frames together with their connections with the platform 25 may be made of sufficient strength to operate effectively and efficiently without the kerf cutters shown in Fig. 1, because it is evident that the supports 204, 213 and 216 are integral extensions of the platform 25 or may be very rigidly secured thereto, since the entire platform is rotated on the truck during the operation of the vertical chain cutters to entirely sever sections of material from a mine wall. However, when the horizontal kerf cutters shown in Fig. 1 are used in conjunction with the loop chain cutters shown in Fig. 10, the supporting structure for the frames U and L need not be made as strong, and therefore cheaper and lighter material may be used because the only cutting strains to which the frames U and L will then be subjected will be that which is necessary to cut the inner vertical kerfs to entirely sever the blocks of material from the mine wall or to finish the kerfs D if the cutter 140 is also used. In other words, only the vertical portions or outer ends of the frames U and L and the corresponding reaches of the cutting chains will be subjected to cutting strains which are comparatively small.

Although a single loop chain cutter extending through the uppermost kerf and the lowermost kerf produced by the uppermost and lowermost kerf cutters shown in Fig. 1 could be used for cutting the inner vertical kerf, and the intermediate kerf cutter shown in Fig. 1 relied on to produce the intermediate horizontal kerf, the double loop chain cutter shown in Fig. 10 is preferable because it distributes the cutting strains between two loop chain cutter units.

Any suitable mechanism may be employed for driving the chains 210 and 211. In the drawings, I have shown the chains 210 and 211 looped around and driven by two sprocket wheels 240 as shown in Fig. 10. These sprocket wheels are mounted upon shafts 241 and 242. The shaft 242 is journaled at one end in a bearing 243 formed at the point where the extension 213 joins the supporting arm 204; at its other end the shaft 242 is journaled in a bearing 244 at the upper end of a standard mounted on the platform 25. The upper shaft 241 is journaled in a single bearing 245 which is formed at the point where the extension 216 joins the upper supporting arm 204. These two shafts 241 and 242 receive power from a countershaft 202 by means of suitable gearing; the shaft 241 having a large gear 248 meshing with the gear 205 on the countershaft 202. The lower shaft 242 carries a similar large gear 246 which is driven by the gear 247 on the countershaft

202. It will be noted that this driving arrangement is such that the chains 210 and 211 travel in the same direction as shown by the arrows in Fig. 10. The lower length of the upper chain 210 and the upper length of the lower chain 211 being coincident with each other in a horizontal plane, necessarily travel in opposite directions in the intermediate horizontal kerf, but this is not objectionable because the rear length is not required to do any cutting.

I find it advisable under certain conditions to employ the supporting plates 171 to operate in the intermediate and lower horizontal kerfs when the loop chain cutters are used in combination with the horizontal kerf cutters or when such loop chain cutters are used separately or without the horizontal kerf cutters shown in Fig. 1. In Fig. 9 I have indicated such supporting devices in dotted outline 171 pivoted to bearing rod 250 extending backwardly from the lower portion of the frame U and connected to resilient cushioning mechanism mounted on the bracket 251 also extending rearwardly from the lower length of the upper frame U. The supporting devices 171 may be identical in construction and mountings with those described in connection with the construction shown in Figs. 1 and 2, the bracket 251 being relied on to support the adjusting bolts 174 and the springs 173 and the bearing rods 250 corresponding with the mechanism adjacent the pivot 170 in Figs. 1 and 2.

It will be obvious, from the foregoing description and comparison of Figs. 1, 2 and 3 with Figs. 9 and 10, that the cutter 140 shown in Fig. 1 and its supporting and operating means may be omitted to make room for the double loop chain cutting mechanism without interfering with the three horizontal kerf cutters mounted as shown in Figs. 1, 2 and 3. When the electric motor M is started, power is immediately transmitted to the gears 246 and 248, as shown in Fig. 9, and the loop chain cutters are operated as well as the three horizontal kerf cutters. Power is transmitted through the gears 206, 207 and 208 to the shaft 34, so that when the clutch 39 is operated in one direction or the other the turntable together with the cutting mechanism mounted thereon may be rotated in the proper direction. In order to accomplish the feeding motion of the cutting apparatus, the brake lever 12, shown in Fig. 2^a, is operated to set the toggle mechanism 9, 10, so as to apply the brake shoes 7 firmly to the wheels of the truck. Therefore while the cutting mechanism, both horizontal and vertical, is started by the starting of the motor, the feeding operation does not begin until the clutch 39 is thrown in and the parts are in proper position to secure the turning of the platform 25. When the clutch 39 is thrown in, the shaft 46 is operated and because the brakes shown in

Fig. 2^a are applied the large gear 48 will be held stationary or locked in fixed position, and consequently the pinion 47 will travel around the gear 48 and thus swing the cutting mechanism during operation. When the platform is thus rotated the pin 54, of course, must be held withdrawn from the notches 55 so as to permit free rotation of the cylindrical flange 27 in the cylindrical cup 21.

In order to adjust the height of the cutting mechanism, I have provided mechanism shown in Fig. 2^a for lifting and lowering the platform on the truck. A shaft E⁵ is mounted in bearings supported by the truck and carries a worm E⁴ meshing with a worm wheel E³ mounted on the cylindrical extension E' of a rotatable bushing provided with a circular flange E² resting on the upper surface of the truck instead of the cup 21. The annular shoulder E² holds the bushing E' in position in a circular opening in the upper side of the truck platform. The sub-platform 26 rests upon and is supported by a large nut E⁶ which is screw-threaded on its interior and is threaded upon a hollow upstanding portion E' of the rotary bushing E'. Thus by turning the hand wheel 310 the worm gearing E⁴, E³ may be operated to turn the bushing E' on the circular bearing E², and the rotation of this bushing causes the threaded upstanding portion E' thereof to screw into or out of the large nut E⁶, thereby lifting or lowering the platform or turntable 25. In order to lock the large nut E⁶ against rotation, it may be firmly secured to the sub-platform 26 or it may be provided with a depending pin E⁸ which slides through an opening in the truck frame E.

The motor M, as shown in Fig. 1, is mounted upon the platform 25 at one side thereof so as to assist in balancing the machine against the weight of the cutting mechanism which is disposed at the opposite side of the platform. In some instances, the balancing weight of the motor may not be sufficient, and it may therefore be desirable to lock the truck to the tracks while at the same time permitting the truck to travel along the track. I therefore provide another set of angularly disposed flanged wheels or rollers 13, the flanges of which, as shown in Fig. 1, engage the under side of the ball of the rails 2 and thereby prevent the truck from being tilted or raised relatively to the track by any strains or unusual loads which may come upon the machine and which might have a tendency to overbalance it. These locking wheels or rollers 13 are mounted at the lower ends of the depending arms 14, which are rotatably mounted upon short shafts 15 outstanding from the frame of the truck, so that the locking wheels may be swung inwardly away from the rails to release the truck from the track in the event that it is desired to do so on such an occasion as when the machine is

to be taken out of the mine or the track re-laid in other parts of the mine. The bearing portions of these rotary arms 14 have gear teeth 16 which mesh with and are driven by worms 17, which are in turn mounted upon the ends of short shafts 18 journaled in bearings 19 on the truck frame and carrying hand wheels 20 by which they may be operated. This construction permits the locking wheels to be readily thrown out of engagement with the rails and at the same time the worm gearing serves to lock the arms in any position to which they have been rotated.

In order to operate the mining machine above described so as to produce long wall cuts as shown in Fig. 13, the brakes shown in Fig. 2^a are first applied to the truck wheels to hold the truck stationary, and the pins 54 are moved to releasing position. The supplemental wheels 13 are also brought into position against the rails so as to keep the truck and mining machine from tipping off the track. By turning the wheel 310 shown in Fig. 2^a, the cutting mechanism may be adjusted to the proper elevation. Assuming that the cutting mechanism has already been moved to a position extending rearwardly from the truck platform 25, as shown in Fig. 1, the motor may be started by means of well known main line and reversing switch mechanism to secure the operation of the loop chain cutters in the directions indicated by the arrows in Fig. 10. Now, by throwing in the clutch 39, as shown in Fig. 2, motion will be transmitted from the gearing shown in Fig. 9 to the shaft 34 and thence to the gear 47 which will travel around the gear 48 now held stationary. When the frame carrying the cutting mechanism has swung to a position where the double loop chain kerf cutter is substantially at right angles to the mine wall, the clutch 39 is thrown to neutral position to stop the feeding operation of the cutting mechanism by stopping the swinging motion of the frames thereof. Now, by thrusting inwardly the pin 54, the flange 27 may be locked to the flange 21, as shown in Fig. 1, so as to lock the platforms 25 and 26 on the truck. The brake mechanism is now released while the supplemental wheels 13 may be left in locking position. The clutch 39 is then again operated to rotate the pinion 47. This time, however, the large gear 48 will be free to rotate while the shaft 46, being mounted in the platform 25, will remain in one position relatively to the truck. Therefore the gear 48 will be rotated to transmit motion to the bevel gears 51, 52, 6 and 4, shown in Fig. 2^a, to propel the truck together with the entire mining machine along the track. The movement of the truck now becomes the feeding movement of the cutting mechanism which may be continued until it is desired to withdraw the cutting mechanism from the mine wall, whereupon the truck is stopped, the

brakes applied, the pin 54 released and the swinging of the cutting mechanism continued forwardly until the cutting mechanism emerges from the mine wall, after which the material entirely severed from the mine wall 5 may be removed by means of suitable loading apparatus. Preferably, however, vertical kerf-cutting mechanism is employed to initially cut the vertical kerfs C (Fig. 13) before the mining machine above described 10 begins to operate, although such vertical kerfs C may be produced after the mining machine completes its operation. It is preferable to cut the vertical kerfs C initially, however, 15 and at frequent intervals, so as to secure blocks of coal of uniform size and also to relieve the weight of the coal on the cutting mechanism in the intermediate and lowermost kerfs. It is obvious that if the vertical 20 kerfs C are produced at frequent intervals, as shown in Fig. 13, the blocks of coal will each fall a short distance one after another and as soon as cut, and in this way the weight on the cutting mechanism is greatly relieved 25 aside from the supporting devices 171, because they will not usually break down until almost entirely severed and then substantially half the weight is taken by the floor of the mine at the other ends of the respective 30 blocks.

In the accompanying drawings I have shown a trailer 171 back of the floor kerf-cutter and another back of the intermediate kerf-cutter. The trailer plates 171 are provided with springs 173 so that such plates 35 may yield to the inequalities of the kerfs and at the same time be sufficiently rigid to properly support the coal above it to keep the same from binding the kerf-cutter, thereby keeping the kerf wide open and affording freedom 40 of feeding movement for the kerf-cutter.

The upward pressures exerted by the trailer plates 171 may be varied by varying the tensions of the springs 173. These trailers 45 operate in upward directions to yieldingly support the cut coal which projects rearwardly over the plate 143 shown in Fig. 2. The yielding supporting devices K also operate to assist in supporting the material above 50 the kerf cut by the kerf-cutter. It will thus be seen that the yielding supporting devices K coact with the yielding trailers 171 in supporting the projecting cut coal during the 55 operation of the kerf-cutting mechanism for the purpose of preventing the coal above the kerf-cutter from sagging to such an extent as to tend to bind the kerf-cutter below. In other words, the yielding devices K and the trailers 171 keep the kerfs spread apart so 60 that the kerf-cutters in advance thereof will have freedom of feeding movement.

It should be understood that when the cutter 140 of Fig. 1 is omitted to make room for the loop chain cutter shown in Fig. 10, the 65 plate 143 and the yielding supporting devices

K and also the trailing devices 171 are mounted on the bearing rods 250 corresponding with the mechanism adjacent the pivot 170 in Figs. 1 and 2. It should also be noted that the uppermost and lowermost runs of the multiple 70 loop chain cutter shown in Fig. 10 are each independently adjusted in elevation so that kerfs may be cut in spaced-apart parallel planes in accordance with the lines of cleavage at the upper and lower limits of the coal 75 vein.

It should be understood that those skilled in the art may make various changes in the details and arrangement of parts herein disclosed without departing from the spirit and scope of my invention as defined by the claims 80 hereto appended. I desire, therefore, not to be restricted to the exact construction herein disclosed.

Having thus fully disclosed an embodiment 85 of my invention, what I desire to secure by Letters Patent of the United States is:

1. In a mining machine, the combination with a multiple loop chain core cutting mechanism having adjacent unobstructed 90 core openings therethrough, of means for feeding said core cutting mechanism transversely of the planes thereof, and means for actuating said cutting mechanism transversely to the direction of feeding movement 95 thereof.

2. In a mining machine, the combination with a supporting frame, of a plurality of loop chain core cutters each having an unobstructed core opening therethrough, means 100 for supporting said core cutters on said frame in position to cut adjacent cores in a mine wall, means for driving said core cutters, and means for swinging said core cutters relatively to said frame to effect arcuate feeding 105 of said core cutters.

3. In a mining machine, the combination with a supporting frame, of a multiple loop chain cutter for producing joining kerfs in a mine wall, each section of said multiple loop chain cutter having an unobstructed core opening therethrough, means for supporting said multiple loop chain cutter on said frame in position to cut multiple cores spaced from 110 said frame, and means for operating said multiple loop chain cutter including feed thereof to produce such kerfs and such cores. 115

4. In a mining machine, the combination with a supporting frame, of a plurality of loop chain core cutters each having an unobstructed core opening therethrough, means for supporting said loop chain core cutters on said supporting frame to extend laterally 120 therefrom relative to the path of travel of said supporting frame, and means for operating said core cutters including rectilinear movement of said supporting frame to secure rectilinear feeding movement of said core cutters to cut a plurality of cores from an up- 125 130

right mine wall spaced laterally from the path of travel of said supporting frame.

5. In a mining machine, the combination with multiple loop chain cutting mechanism having adjacent unobstructed core openings therethrough, of means for operating said cutting mechanism to cut an E-shaped kerf in a mine wall, and adjacent cores bounded by such kerfs and the face of the mine wall, and
10 means for supporting the aforesaid structure in position for operation on material in its native bed.

6. In a mining machine, the combination with a supporting frame, of multiple loop 15 chain core cutting mechanism, means for supporting said core cutting mechanism on said frame in position to cut superposed U-shaped kerfs in a mine wall around cores projecting through said unobstructed core openings and
20 extending along positions separate from said frame, and means for operating said core cutting mechanism including the feed thereof to secure the cutting of such cores spaced from said frame.

25 7. In a mining machine, the combination with a plurality of loop chain core cutters each having an unobstructed core opening therethrough, of means for supporting said chain cutters in different planes of operation, and means for operating said chain cutters to cause each of them to cut a core of material
30 in a mine wall.

35 8. In a mining machine, the combination with two loop chain kerf cutters each having unobstructed core openings therethrough for the passage of cut material, of a frame for supporting said chain cutters to cause adjacent runs thereof to travel in an intermediate kerf, and means for operating said kerf cutters including the feed thereof to cut kerfs in
40 a mine wall including such intermediate kerf.

45 9. The combination with two loop chain cutters each having an unobstructed core opening therethrough, of mechanism for supporting said chain cutters in superposed positions with predetermined lengths thereof in the same plane, and means for operating said chain cutters to produce a plurality of kerfs in a mine wall around cores respectively projecting through said cutters.

50 10. In a mining machine, the combination with supporting framework, of a multiple loop chain core cutter having adjacent unobstructed core openings extending therethrough, means for supporting said multiple loop chain core cutter on said framework for arcuate feeding movement relatively thereto, means for driving said multiple loop chain core cutter, and means for swinging the
55 multiple loop chain core cutter relatively to said framework to secure arcuate feeding movement of said chain core cutter to cut adjacent cores spaced from said framework.

60 11. In a mining machine, the combination with a plurality of loop chain core cutters each

having an unobstructed core opening therethrough, of framework for supporting said loop chain core cutters in different planes but in such relation to each other as to produce immediately adjacent cores respectively extending through said unobstructed core openings, and means for operating said loop chain core cutters to cut communicating kerfs back of the cores. 70

12. In a mining machine, the combination with supporting framework, of a multiple core cutter each section having an unobstructed core opening therethrough, means for pivotally supporting said multiple core cutter on said framework for feeding movement relatively thereto, and means for operating said multiple core cutter including swinging feeding movement thereof relatively to said framework to simultaneously cut adjacent cores respectively extending through 85 the unobstructed core openings of said sections.

13. In a mining machine, the combination with a portable frame, of a supplemental frame rotatably mounted thereon, a multiple loop cutter having adjacent unobstructed core openings therethrough, said cutter being mounted on said supplemental frame to move bodily therewith, and means for operating said multiple loop cutter to produce 90 continuous kerfs in a mine wall around adjacent cores respectively extending through
95 said unobstructed core openings.

14. In a mining machine, the combination with a main supporting frame, of a double 100 cutter frame having unobstructed core openings therethrough in close proximity to each other with the intermediate portion of said double frame in fixed relation to said supporting frame, travelling chain cutting mechanism mounted on said double frame, means for operating said chain cutting mechanism including the feed thereof by movement of said double frame to cut juxtaposed cores of material in a mine wall, and means for individually adjusting the spacing of the runs of said chain cutting mechanism on both 110 sides of the intermediate run along that portion of said double frame mounted in fixed relation to said supporting frame. 115

15. In a mining machine, the combination with a plurality of loop chain cutters, of a frame for each of said loop chain cutters, each of said frames having an unobstructed core opening therethrough, a main supporting 120 frame, connections between said loop cutter frames and said main supporting frame to support said chain cutters for operation in different but adjacent upright planes with a run of one of said loop cutter frames back of 125 a run of the other loop cutter frame intermediate the floor and roof of the mine chamber, means for actuating said chain cutters, and mechanism for feeding said chain cutter frames to cause said chain cutters to produce 130

a plurality of horizontal kerfs connected by vertical kerfs at their rear ends.

16. In a mining machine, the combination with two loop chain cutters, of a main supporting frame, a frame for each of said loop cutters, each of said frames having an unobstructed core opening therethrough, supplemental frame-work for supporting said loop cutter frames on said main supporting frame with the lengths of said loop chain cutters between cores in substantially the same plane, the planes of said chain cutters transversely of the cores being in different but adjacent planes, means for actuating said chain cutters, and means for feeding said chain cutters together with their frames to form a double U-shaped kerf in a mine wall and produce juxtaposed cores.

17. In a mining machine, the combination with a truck, of a main frame mounted on said truck for arcuate movement on an upright axis, brake mechanism for holding said truck stationary, a multiple loop core cutting having a plurality of immediately adjacent unobstructed core openings therethrough and mounted on said main frame to move bodily therewith, mechanism for propelling said truck to secure feeding movement of said core cutter along the mine wall to cut parallel cores respectively extending through said unobstructed core openings, and means for effecting arcuate movement of said main frame on said truck to secure swinging feeding movement of said multiple core cutter in an arc.

18. The combination with a loop chain cutter, a guide frame therefor, means for adjusting the width of said guide frame, means for adjusting the length of said guide frame, and means for operating said chain cutter to produce a U-shaped kerf in the mine wall in accordance with the adjustments of said frame.

19. The combination with a chain cutter, of a guide frame therefor, means for increasing the width of said frame and decreasing its length or decreasing the width of said frame and increasing its length to adjust the dimension of the cut without substantially varying the length of the path of travel of said chain cutter, and means for operating said chain cutter to produce a U-shaped kerf in a mine wall in accordance with the adjustments of said frame.

20. In a mining machine, the combination with a loop chain cutter, of a frame therefor having an unobstructed core opening therethrough, means for operating said loop chain cutter including the movement of said frame to feed said cutter while the core cut thereby extends through said unobstructed core opening, frame-work for supporting the aforesaid parts, a predetermined length of said chain cutter being adapted to extend in a plane substantially level with the mine floor for feed-

ing movement along such plane or a plane parallel thereto, and means for adjusting the height of said predetermined length for operation in substantially horizontal planes parallel to the plane of the mine floor.

21. In a mining machine, the combination with a loop chain cutter, of a frame therefor having an unobstructed core opening therethrough, means for supporting said loop chain cutter and said frame in a substantially vertical plane with the lower length of said chain cutter in a plane parallel to the floor of the mine and adjacent thereto, means for adjusting the elevation of such lower length of said chain cutter relatively to the remainder of the cutter to operate substantially in the plane of the floor or in planes substantially above the plane of the mine floor, and means for operating said chain cutter including the feed thereof by movement of said chain cutter frame for the various adjustments of such lower length.

22. In a mining machine, the combination with a supporting frame, of a supplemental frame rotatably mounted on said supporting frame, a plurality of spaced-apart plane kerf cutters on said supplemental frame, a loop chain core cutter comprising a cutter frame having an unobstructed core opening therethrough and means detachably connecting said cutter frame to said supplemental frame in position to cause the upper and lower runs of said core cutter to extend along the kerfs produced by said kerf cutters, and to cause the outer upright run of said core cutter to cut a communicating kerf between the upper and lower plane kerfs, means for driving said kerf cutters and said core cutter, and means for moving said supplemental frame arcuately relatively to said supporting frame to effect arcuate feeding movement of said plane kerf cutters when said core cutter is detached, and to effect feeding movement of said kerf cutters and said core cutter when the latter is connected to said supplemental frame.

23. In a mining machine, the combination with a main supporting frame, of a plurality of loop chain core cutters each comprising a rectangular frame detachably connected to said main supporting frame, each of said rectangular frames having an unobstructed core opening therethrough, and means for operating said chain cutters including the feed thereof to cut immediately adjacent cores in a mine wall or a single core when one of said frames is detached.

24. In a mining machine, the combination with a supporting frame, of spaced apart plane kerf cutters mounted on said supporting frame, a loop chain core cutter comprising a cutter frame having an unobstructed core opening therethrough and having spaced apart runs in the planes of movement of the respective plane kerf cutters, a connection between said cutter frame and said supporting

frame to permit said cutter frame together with said chain core cutter to be readily detached from said supporting frame, means for operating said plane kerf cutters including the feed thereof, and means for operating said loop chain core cutter including the feed thereof to follow the feeding movement of said plane kerf cutters.

25. In a mining machine, the combination with a main supporting frame, of loop kerf cutting mechanism having an unobstructed core opening therethrough and comprising a cutter frame, a connection between said cutter frame and said main supporting frame to permit said cutter frame to be detached from said supporting frame, an additional loop kerf cutting mechanism having an unobstructed core opening therethrough adjacent the first named core opening and comprising an additional cutter frame connected to said main supporting frame, and means for operating said first named kerf cutting mechanism and said additional kerf cutting mechanism including the feed thereof to cut cores immediately adjacent to each other in a mine wall.

26. In a mining machine, the combination with a loop chain core cutter comprising a frame having an unobstructed core opening therethrough, of framework for supporting said chain cutter in a substantially vertical plane, a trailer connected to the lower horizontal portion of said cutter frame and extending back therefrom to assist in supporting the material above the lower horizontal kerf produced by said cutter, and means for operating said cutter including feeding movement thereof while the movement of said cutter frame drags along behind it said trailer.

27. In a mining machine, the combination with a multiple loop chain cutter comprising a frame having juxtaposed unobstructed core openings therethrough, of means for operating said multiple loop chain cutter to produce a plurality of horizontal spaced apart kerfs and upright connecting kerfs, and trailing mechanism following the lowermost and intermediate lengths of said frame for assisting in supporting material above the kerfs below the uppermost kerf.

28. In a mining machine, the combination with a supporting frame, of a plurality of spaced apart kerf cutters mounted on said frame, means for operating said kerf cutters to produce spaced apart kerfs in a mine wall, a multiple loop cutter having adjacent unobstructed openings therethrough for the passage of cut material, means for operating said multiple loop cutter to produce kerfs spaced back from the face of the mine wall and connecting the inner ends of the said spaced apart kerfs, and connections for mounting the aforesaid parts cooperatively on said supporting frame.

29. The combination with a plurality of kerf cutters substantially parallel to each

other and spaced apart, of a multiple loop cutter extending through the kerfs produced by said parallel kerf cutters, and means for operating said kerf cutters and said multiple loop cutters to produce communicating kerfs in a mine wall and entirely sever a plurality of sections of material therefrom.

30. The combination with a plurality of kerf cutters each horizontal in elevation, a loop cutter extending through the kerfs produced by said first named kerf cutters, a frame for supporting said first named kerf cutters for operation ahead of said loop cutter, means for rectilinearly adjusting the elevation of said cutters and means for operating said kerf cutters and said loop cutters simultaneously to produce a U-shaped kerf in a mine wall.

31. The combination with a plurality of kerf cutters, of means for supporting said kerf cutters in positions spaced apart but substantially parallel to each other, mechanism for operating said kerf cutters to simultaneously produce a plurality of spaced apart parallel kerfs in a mine wall, a multiple loop chain cutter having unobstructed openings therethrough for the passage of cut material, and means for operating said multiple loop cutter to produce connecting kerfs between the inner ends of the first named kerfs spaced back from the face of the mine wall.

32. The combination with a plurality of horizontal kerf cutters, of means for supporting the same parallel to each other and spaced apart, means for operating said kerf cutters to produce substantially parallel kerfs spaced apart in a mine wall, a loop cutter extending through the aforesaid parallel kerfs for producing a connecting kerf between the intermediate end thereof, and means for varying the elevation of all of said cutters in their entirety while maintaining their predetermined relation and while maintaining said first-named cutters horizontally.

33. The combination with a plurality of horizontal kerf cutters substantially parallel to each other and spaced apart, of means for actuating said kerf cutters, a plurality of loop chain cutters for producing vertical connecting kerfs at the rear ends of said horizontal kerfs, means for supporting said loop chain cutters to extend through the kerfs produced by said first named kerf cutters, means for actuating said loop chain cutters, a main frame for supporting all of the aforesaid parts, and means for moving said frame to fit the kerf cutting mechanism and said loop chain cutters to effect the production of communicating U-shaped kerfs in a mine wall.

34. In a mining machine, the combination with a truck, of a loop chain core-cutter having an unobstructed core-opening therethrough and comprising an upper run adapted to occupy a position in an upper horizontal plane, of a supporting frame

therefor mounted on said track, means for adjusting the height of the entire core-cutter relatively to said truck while the latter remains stationary, to adjust the height of the kerf-cut by said upper run, and mechanism 5 for operating said core-cutter including the feed thereof in its adjusted position to cut a substantially horizontal kerf at the roof of the mine chamber at the adjusted elevation.

10 35. In a mining machine, the combination with a loop chain core cutter having an unobstructed core opening therethrough and comprising a cutter frame, of a main frame rigidly connected to said chain cutter frame, 15 means for adjusting the elevation of the core cutter in its entirety relatively to said main frame, and means for operating said core cutter in the positions to which adjusted in elevation.

20 36. In a mining machine, the combination with multiple loop chain cutting mechanism having immediately adjacent unobstructed core-openings extending transversely therethrough, of means for operating said cutting mechanism, and means for feeding said cutting mechanism to cut closely adjacent cores by a single operation across the mine wall.

25 37. In a mining machine, the combination with a supporting frame, of a plurality of 30 loop chain core cutters each having an unobstructed core opening therethrough, means for supporting said loop chain core cutters on said frame in position to simultaneously 35 cut a plurality of closely adjacent cores in a mine wall spaced from said frame, and means for operating said loop chain core cutters including feed thereof to simultaneously cut such a plurality of closely adjacent cores spaced from said frame.

40 38. In a mining machine, the combination with two loop chain core cutters each having a predetermined run extending along a kerf between the cores produced by said cutters, of means for actuating said cutters, and means 45 for feeding said cutters to produce adjacent cores in a mine wall.

39. In a mining machine, the combination with a supporting frame, of a loop chain core cutter mounted on said frame, an additional 50 loop chain core cutter mounted on said frame, of means for supporting said additional loop chain core cutter in a plane following the plane of said first-named core cutter, means for actuating said chain cutters, and means 55 for feeding said core cutters during the actuation thereof to cut juxtaposed cores in a mine wall.

40 40. In a mining machine, the combination with a plurality of spaced-apart kerf cutters, 55 of a loop core cutter having an unobstructed core-opening therethrough and extending along the kerfs produced by said spaced-apart kerf cutters, and means for operating said kerf cutters and said loop core cutter to cut a core of material in a mine wall.

41. In a mining machine, the combination with a plurality of spaced-apart plane kerf cutters, of a loop chain core cutter for cutting a kerf between the kerfs produced by said kerf cutters and spaced back from the face 70 of the mine wall and approximately parallel thereto, means for adjusting the elevation of one of said plane kerf cutters relatively to the other and means for operating said kerf cutters and said core cutter to cut a core of 75 material in its native bed.

42. In a mining machine, the combination with a plurality of spaced-apart kerf cutters each horizontal in elevation, of a loop chain core cutter following said spaced-apart 80 cutters and capable of cutting a kerf spaced back from the mine wall and connecting the kerfs cut by said kerf cutters, means for adjusting the elevation of said first-named kerf cutters while maintained horizontal in elevation and means for operating said kerf cutters and said core cutter to cut a core of 85 material in a mine wall.

43. In a mining machine, the combination with a supporting frame, of a plurality of 90 spaced-apart kerf cutters mounted on said frame, a loop chain core cutter having an unobstructed core opening therethrough and mounted on said supporting frame with its upper and lower runs approximately in the 95 respective planes of said spaced-apart kerf cutters and its outer upright run in position to cut a communicating kerf between the kerfs cut by said spaced-apart kerf cutters, means for adjusting and spacing between 100 said first-named kerf cutters and means for operating said spaced-apart kerf cutters and said core cutter, including the feed of all of said cutters, to cooperate in the cutting of a core of material in its native bed.

44. In a mining machine, the combination with a plurality of spaced-apart plane kerf cutters, of a supporting frame therefor, means for actuating said kerf cutters, means for moving said supporting frame to effect the feed of said kerf cutters, a loop chain core cutter mounted on said supporting frame behind said kerf cutters relatively to the feed thereof, and means for actuating said loop chain core cutter to effect the cutting of a 110 connecting kerf between the kerfs cut by said plane kerf cutters.

45. In a mining machine, the combination with a supporting frame, of cutting mechanism having adjacent unobstructed core openings extending therethrough, means for pivotally supporting said cutting mechanism on said frame for arcuate swinging feeding movement relatively thereto, means for driving said cutting mechanism, and means for swinging said cutting mechanism relatively to said frame to effect arcuate feeding movement of said cutting mechanism to cut arcuate juxtaposed cores while said frame remains stationary.

46. In a mining machine, the combination with a supporting frame, of apparatus for simultaneously cutting a plurality of juxtaposed cores of material in a mine wall, means for supporting said multiple cutting apparatus on said frame for arcuate feeding movement relatively thereto, means for holding said cutting apparatus against such arcuate movement relatively to said frame, means for driving said cutting apparatus, means for swinging said cutting apparatus relatively to said frame to effect feeding movement thereof into an upright mine wall and out from the mine wall, and means for moving the supporting frame rectilinearly to effect rectilinear feeding movement of said cutting apparatus along a mine wall between its arcuate cuts and while said cutting apparatus is held against arcuate movement relatively to said frame.

47. In a track mounted mining apparatus adapted to cut a plurality of superposed horizontal cores extending across its front from one side of the track to the other, the combination with a rigid base frame, supporting wheels therefor resting upon and braced by the track, a laterally movable cutter arm carried by the base frame and extending therefrom in horizontal planes, endless chain cutters movable along the cutter arm around juxtaposed unobstructed core openings and in paths in an upright plane throughout, a chain driving motor connected to said cutter arm to move bodily therewith, said cutter arm having upper and lower straight runs for said chain cutters, power transmission mechanism between said motor and said chain cutters for driving the latter, power actuated means for moving said cutter arm in an arc to feed said chain cutters into a mine wall and in an arc out from the mine wall relatively to said base frame, and propelling mechanism for moving said base frame along said track to feed said chain cutters rectilinearly between said arcuate feeding movements.

48. In a mining machine, the combination with a plurality of plane kerf cutters, of a loop chain core cutter co-operatively related to said kerf cutters, of a supporting frame for carrying said kerf cutters ahead of said core cutter, and apparatus for operating said kerf cutters and said core cutter including swinging thereof in an arc into a mine wall, feeding along a mine wall, and swinging in an arc out from a mine wall.

49. In a mining machine, the combination with a plurality of plane kerf cutters comprising upper, lower and intermediate kerf cutters, of a plurality of loop chain core cutters mounted back of the kerf cutters, means for actuating said kerf cutters and said loop chain core cutters, and means for feeding said kerf cutters and said loop chain core cutters to cut adjacent cores of material in its native bed.

50. In a mining machine, the combination with a supporting frame, of a plurality of spaced apart kerf cutters comprising upper, lower and intermediate kerf cutters mounted on said supporting frame, a plurality of loop chain core cutters mounted on said supporting frame in a predetermined relation to said spaced apart kerf cutters to cooperate therewith to cut adjacent cores of material, and means for simultaneously operating said spaced apart kerf cutters and said loop chain core cutters to cut such adjacent cores.

51. In a mining machine, the combination with a plurality of spaced-apart plane kerf cutters comprising upper, lower and intermediate kerf cutters, of a plurality of loop chain core cutters each having upper and lower straight runs, a supporting frame for carrying said loop chain core cutters with said straight runs in predetermined positions back of respective kerf cutters, and means for operating said kerf cutters and said loop chain core cutters to cut adjacent cores in a mass of material.

52. In a mining machine, the combination with a ceiling plane kerf cutter, of a floor plane kerf cutter, an intermediate plane kerf cutter, an upper loop chain core cutter having an upper straight run back of the ceiling kerf cutter and in the plane thereof, a lower straight run back of the intermediate kerf cutter and in the plane thereof, a lower loop chain core cutter having an upper straight run back of the intermediate kerf cutter and in the plane thereof, a lower straight run back of the floor kerf cutter and in the plane thereof, said loop chain core cutters also having vertical runs for connecting the ceiling and floor kerfs with the intermediate kerf spaced back from the face of the mine wall, a supporting frame for carrying said ceiling, floor and intermediate kerf cutters in a predetermined relation to said loop chain core cutter and ahead of the same, and means for operating said kerf cutters and said loop chain core cutters including the feed thereof to cut superposed cores of material in a mine wall.

53. In a mining machine, the combination with a main frame, of a supplemental frame, a plurality of spaced-apart plane kerf cutters mounted on said supplemental frame, a plurality of loop chain core cutters mounted on said supplemental frame back of said plane kerf cutters and in position to cut connecting kerfs spaced back from the mine wall between the kerfs cut by said kerf cutters, means mounted on said supplemental frame for actuating said kerf cutters and said loop chain core cutters, means for swinging said supplemental frame on said main frame, and mechanism for moving all of the aforesaid parts bodily to effect the feeding of said

- kerf cutters and said core cutters along a mine wall.
54. In a mining machine, the combination with a supporting frame, of core cutting mechanism comprising a cutter frame, and a yielding device additional to the cutter-frame and extending back from the core cutting mechanism and below the core tending to support the latter.
- 10 55. In a mining machine, the combination with loop chain core cutting mechanism comprising a frame having an unobstructed core opening therethrough and including a lower straight run, and mechanism additional to such frame and separate therefrom and extending back from said lower straight run in position tending to support the core projecting through said frame.
- 20 56. In a mining machine, the combination with core cutting mechanism having an unobstructed core opening therethrough, of a platform, and means for supporting said platform back of a portion of said core cutting mechanism and separately therefrom in position to support the core projecting through said core cutting mechanism, and thus take the weight thereof from said core cutting mechanism.
- 25 57. In a mining machine, the combination with a ceiling plane kerf cutter, of a floor plane kerf cutter, an intermediate plane kerf cutter, upper and lower loop chain core cutters each having an upper and lower straight run movable along a plane kerf previously produced by the advance kerf cutter, a supporting frame for carrying said kerf cutters and loop chain core cutters in predetermined relation and with the lower straight run of the upper loop chain core cutter and the upper straight run of the lower loop chain core cutter approximately in the same plane as the intermediate plane kerf cutter, means for actuating said kerf cutters and said loop chain core cutters, means for moving said supporting frame to effect the feeding of said kerf cutters and said core cutters, and pivoted spring-pressed platforms immediately back of the runs of said loop chain core cutter in the intermediate kerf and the lower run of the loop chain core cutter in the floor kerf, said platforms tending to support the cores projecting through said core cutters and thereby taking sagging weight of said projecting cores from the loop chain core cutters.
- 30 58. In a mining machine, the combination with a plurality of spaced apart plane kerf cutters mounted for feeding movement in approximately horizontal parallel planes across a mine wall, of a plurality of loop chain core cutters each having upper and lower straight runs following in the wake of respective kerf cutters and cutting connecting kerfs between said parallel kerfs, a supporting frame for carrying said core cutters immediately back of said kerf cutters, means for simultaneously actuating said kerf cutters and said loop chain core cutters, and means for effecting the simultaneous feeding of said kerf cutters and said loop chain core cutters by movement of said supporting frame.
- 35 59. In a mining machine, the combination with a supporting frame, of multiple core cutting mechanism comprising a plurality of chain kerf cutters, means for pivotally supporting said multiple core cutting mechanism on said frame for swinging feeding movement on an upright axis in position to cut juxtaposed cores in a mine wall, means for driving said core cutting mechanism, and mechanism for feeding said core cutting mechanism by swinging the same in an arc relatively to said frame to simultaneously cut a plurality of arcuate juxtaposed cores in the mine wall while said frame remains stationary.
- 40 60. In a mining machine, the combination with a supporting frame, of multiple core cutting mechanism comprising a plurality of endless chain cutters each having an unobstructed core opening therethrough, means for supporting said core cutting mechanism on said frame in position to cut superposed and juxtaposed crescent-shaped cores of material in an upright mine wall, means for driving said core cutting mechanism, and apparatus for feeding said core cutting mechanism in an arc relatively to said frame while the latter remains stationary to entirely cut from the upright mine wall such superposed and juxtaposed crescent-shaped cores of material.
- 45 61. In a mining machine, the combination with a truck adapted to travel on a mine track, of a supporting frame, a loop chain core cutter comprising a guiding frame having an unobstructed core opening therethrough, means for adjusting the elevation of the lowermost length of said chain cutter relatively to the remainder thereof for operation in planes substantially parallel to each other, and mechanism for operating said core cutter including feed thereof in a direction transverse to the direction of travel of the chain cutter and in the various adjusted positions of the latter.
- 50 62. In a mining machine, the combination with a loop chain cutter, of a guide frame having an unobstructed core opening therethrough and comprising a relatively movable section adapted to extend along the floor of a mine chamber or in planes parallel thereto, means for rectilinearly adjusting the position of said movable section to vary the elevation of the plane of operation of the lowermost run of said chain cutter, means for supporting said chain cutter in an upright plane with its lower length at or near the floor of said mine chamber, and means for operating said chain cutter in the various positions of adjustment of said lowermost run including

feed thereof transversely to the upright plane of said cutter frame while said chain cutter travels around the unobstructed core opening through said cutter frame.

63. In a mining machine, the combination with a multiple loop core cutter having adjacent unobstructed core openings therethrough, of means for independently adjusting the elevation of the uppermost and lowermost runs of said multiple core cutter, and means for operating said multiple loop core cutter including feed thereof to cut cores adjacent to each other and respectively extending through said unobstructed core openings.

64. In a mining machine, the combination with a supporting frame, of core cutting mechanism comprising a loop chain core cutter having an unobstructed core opening therethrough and also comprising upper and lower kerf cutters spaced apart in accordance with the spacing of the upper and lower runs of said loop chain cutter, means for supporting said core cutting mechanism on said frame in position to cut a core in a mine wall, means for independently adjusting in elevation each of said upper and lower kerf cutters relatively to the other and relatively to said frame, and means for operating said core cutting mechanism including feed thereof to cut said core.

65. In a mining machine, the combination with core cutting mechanism comprising means for cutting a kerf in a substantially horizontal plane at the floor of a mine chamber and means for cutting a kerf in a substantially horizontal plane at the roof of such mine chamber, of means for independently adjusting the floor kerf cutting means and the roof kerf cutting to vary the elevation of either the floor kerf or the roof kerf independently of the elevation of the other, means for bodily adjusting the elevation of all of said cutting mechanism, and means for operating said core cutting mechanism including the feed thereof.

66. In a mining machine, the combination with loop chain core-cutting mechanism comprising spaced-apart cutting means, of mechanism for independently adjusting the distance of each kerf-cutting means, and means for operating said core-cutting mechanism including the feed thereof to cut spaced-apart kerfs and a communicating back kerf.

67. In a mining machine, the combination with loop chain core cutting mechanism comprising guiding frame-work having spaced apart straight runs for the chain cutting mechanism, of means for independently adjusting the position of each of said runs and its distance from the other run, and means for operating said loop chain core cutting mechanism including the feed of said spaced apart runs along spaced apart plane kerfs.

68. In a mining machine, the combination with loop chain core cutting mechanism comprising a rigid intermediate frame and a spaced apart movable frame, of mechanism individual to each of said movable frames for adjustably holding the respective movable frames in position on said intermediate frame, and means for operating said core cutting mechanism by causing the chain cutting mechanism to travel along the guides outside the intermediate and spaced apart movable frames and by causing said intermediate frame to swing transversely thereof to effect the feed of said core cutting mechanism and effect the cutting of spaced apart kerfs in accordance with the independent adjustments of said movable frames.

69. In a mining machine, the combination with loop chain core cutting mechanism comprising an intermediate frame and spaced apart frames movable toward and from each other relatively to said intermediate frame, of mechanism comprising spaced apart screw threaded rods mounted on said intermediate frame and connected respectively to said spaced apart movable frames for independently adjusting the distance of each movable frame from the other to vary the distance between the kerfs produced by the chain cutter mechanism extending along said movable frames, and means for operating said loop chain core cutting mechanism including feed thereof transversely of the direction of travel of the chain cutting mechanism.

70. In a mining machine, the combination with a supporting frame, of a loop chain guiding frame having an unobstructed core opening therethrough and comprising one section rigidly connected to said supporting frame and another section connected to said first named section for movement relatively thereto, an endless chain cutter mounted on said sections to travel along the same around said unobstructed core opening, means mounted on said supporting frame for actuating said chain to cause the same to travel along said sectional frames, a plane kerf cutter mounted on said supporting frame for operation in advance of said movable section, means for adjusting the position of said plane kerf cutter to vary the plane of the kerf produced thereby, means for adjusting the position of said movable section relatively to said rigid section to correspond to the adjustment of said plane kerf cutter, and means for operating said plane kerf cutter and said chain cutter including the feed of both transversely of the direction of travel of said chain cutter.

71. In a mining machine, the combination with a supporting frame, of a plurality of core cutting devices each comprising a separate frame having an unobstructed core opening therethrough and each detachably mounted on said supporting frame for bodily movement therewith, of means for operating

said core cutting devices including feed thereof to cut a single core or a plurality of closely adjacent cores in a mine wall.

72. In a mining machine, the combination with a multiple core cutter comprising separate detachable frames each having an unobstructed core opening therethrough, and means for operating said multiple core cutter to cut a plurality of closely adjacent cores extending through said unobstructed core openings.

73. In a mining machine, the combination with a supporting frame, of two loop chain core cutting devices each comprising a frame having an unobstructed core opening therethrough and each detachably mounted on said supporting frame in position for the cutting of superposed cores closely adjacent to each other and extending through said unobstructed core openings, means for actuating said chains to cause them to travel around their respective frames, and mechanism for moving said supporting frame and the detachable frames mounted thereon to effect feeding movement of said core cutting devices.

74. In a mining machine, the combination with a supporting frame, of means carried by said frame for the detachable connection thereto of separate core cutting devices each comprising a frame having an unobstructed core opening therethrough in closely adjacent relation, and each having an endless chain cutter guided thereon, mechanism on said supporting frame and comprising spaced apart sprocket wheels in position for engaging and driving the respective chain cutters, and mechanism for moving said supporting frame together with said attachments and said driving mechanism to effect the feed of either of said core cutting devices or both of them.

75. In a mining machine, the combination with a loop chain core cutter comprising a cutter frame having an unobstructed core opening therethrough, of means for operating said core cutter including feeding movement thereof, and a device mounted to trail a predetermined distance behind said cutter frame in position to project into the kerf back of the lower run of the core cutter and movable bodily with the latter to support material above said kerf cutter to prevent the same from retarding the feeding motion of said core cutter.

76. In a mining machine, the combination with core cutting mechanism having an unobstructed core opening therethrough, of means for operating said core cutting mechanism including the feed thereof, and a device connected to move bodily with said core cutting mechanism and pivoted thereto for movement relatively thereto in position to have a tendency to support material above the same and thereby relieve said core cutting

mechanism from the weight of such material and permit said core cutting mechanism to have freer feeding movement.

77. In a mining machine, the combination with loop chain core cutting mechanism comprising a frame having an unobstructed core opening therethrough, of means for operating said core cutting mechanism including the feed thereof, and an independent supporting member pivotally and yieldingly mounted to trail a predetermined distance behind said frame and below the core of material extending through said unobstructed core opening.

78. In a mining machine, the combination with a wheel-supported rigid base frame adapted to run upon and be braced by the rails of a mine track, of a multiple loop chain core-cutter carried by said base frame and projecting horizontally therefrom in upright planes, supporting means between said cutter and said base frame and comprising an upright support extending upwardly from said base frame, means for guiding said supporting means upwardly and downwardly rectilinearly, means for adjusting said supporting means vertically and rectilinearly in relation to said base frame to secure rectilinear and vertical adjustment of the entire multiple loop chain core-cutter, and means for operating said cutter including feed thereof to cut parallel closely adjacent cores in a mine wall.

79. In a mining machine, the combination with a wheel supported rigid base frame adapted to run upon a mine track, of a loop chain core-cutter having an unobstructed core-opening therethrough, a rigid base frame, wheels for mounting said base frame on a mine track, a supplemental frame carried by said base frame, means for supporting said supplemental frame on said base frame and confining and guiding said supplemental frame along up and down rectilinear paths of movement of said supplemental frame, means for supporting said core-cutter on said supplemental frame to occupy an upright position and for bodily rectilinear movements therewith up and down in its entirety, and means for operating said core-cutter including feed thereof at any of its adjusted elevations to cut a core in a mine wall in a general horizontal direction.

80. In a mining machine, the combination with a wheeled truck adapted to run on a track in a mine, of a supplemental frame mounted on said truck for up and down movement relatively thereto, telescoping guiding connections between said truck and said supplemental frame for confining such movements of said supplemental frame relatively to said truck to rectilinear movements, means for adjusting the elevation of said supplemental frame relatively to said truck, a loop chain core-cutter rigidly connected to said

- supplemental frame and movable bodily therewith, said core-cutter occupying an upright position and partaking in its entirety of the rectilinear up and down movements of said supplemental frame to secure adjustment in elevation of the entire core-cutter, means for driving said chain core-cutter, means for rotating said supplemental frame on said truck to effect arcuate feeding movement of said core-cutter, and means for propelling said truck together with the supplemental frame mounted thereon to effect rectilinear feeding movement of said core-cutter.
81. In a mining machine, the combination with supporting framework, of two core cutters each having an unobstructed core opening therethrough, means for mounting said core cutters on said framework in position to cut closely adjacent cores extending through the respective core openings, means for adjusting said core cutters to vary the location of the division between said cores, and means for operating said core cutters to cut such closely adjacent cores with the core cutters in adjusted positions.
82. In a mining machine, the combination with supporting framework, of a multiple core-cutter having closely adjacent unobstructed core-openings extending therethrough, means for operating said multiple core-cutter to cut three spaced-apart kerfs extending into the mine wall from the face thereof and communicating back kerfs spaced back from the face of the mine wall to produce closely adjacent cores extending through the respective core-openings, and means for rectilinearly adjusting the core-cutting mechanism to vary the height of the intermediate kerf.
83. In a mining machine, the combination with supporting framework, of two core-cutters each having an unobstructed core-opening therethrough and each comprising means for cutting a kerf between the cores, means for operating said core-cutters to cut cores on both sides of said intermediate kerf and extending respectively through said core-openings, and means for adjusting the position of the mechanism for cutting the intermediate kerf to vary the position of the kerf between said cores.
84. In a mining machine, the combination with supporting framework, of a multiple core-cutter mounted on said framework in position to cut three spaced-apart kerfs, means for operating said core-cutters to cut closely adjacent cores extending through the respective core-openings on both sides of the intermediate kerf, and means for effecting adjustment of said multiple core-cutter to vary the position of the cutting of the intermediate kerf relatively to the other kerfs without varying the position of the kerfs spaced from the intermediate kerf.

85. In a mining machine, the combination with a main frame, of a supplemental frame mounted on said main frame for up and down movement relatively thereto, two loop chain core-cutters mounted on said supplemental frame to occupy upright positions with unobstructed core-openings therethrough, means for operating said loop chain core-cutters to cut closely adjacent cores with a division kerf between them, means for adjusting the position of said supplemental frame relatively to said main frame to vary the location of such intermediate kerf, and means for adjusting those portions of said loop chain core-cutters spaced from said intermediate kerf to cause the kerfs spaced from the intermediate kerf to remain unvaried for various adjustments of the intermediate kerf.
86. In a mining machine, the combination with two endless loop chain cutters, of framework for carrying and guiding said loop chain cutters around closely adjacent unobstructed core-openings extending through said framework in position for cutting three spaced-apart kerfs, means for operating said loop chain cutters including movement of said framework to effect the feed of said cutters to cut closely adjacent cores extending respectively through said core-openings, and means for effecting the adjustment of said framework to vary the position of the intermediate kerf without varying the position of the kerfs spaced therefrom.
87. In a mining machine, the combination with a main frame, of a supplemental frame, two endless loop chain cutters, two cutter frames rigidly connected to said supplemental frame to move bodily therewith, one of said cutter frames being adapted for one of said loop chain cutters and the other cutter frame being adapted for the other cutter to cut closely adjacent cores extending through unobstructed core-openings in said cutter frames, means for operating said loop chain cutters including movement of said supplemental frame to effect the feed of said cutters to cut upper, lower and intermediate kerfs extending into the mine wall from the face thereof, and to cut upright communicating kerfs spaced back from the face of the mine wall, adjusting mechanism mounted on each of said cutter frames for varying the position of sections thereof, the second for the upper kerf being adjustable in elevation and the second for the lower kerf being adjustable in elevation relatively to said supporting frame, and means for adjusting the elevation of said supplemental frame on said main frame to vary the elevation of said core-cutter frames including the elevation of the intermediate kerf between the said cores, whereby the elevation of each of the upper, lower and intermediate kerfs may be adjusted independently of each other, or any one

of them adjusted in elevation while the other two are retained at the same elevation.

88. In a mining machine, the combination with supporting framework, of a plurality of core cutters each having an unobstructed core opening therethrough, means for operating said core cutters including the swinging feed thereof, and mechanism for pivotally supporting said core cutters on said supporting framework to enable the cutting of cores immediately adjacent each other with the material between the same cut away.

89. In a mining machine, the combination with multiple chain cutting mechanism, of means for pivotally supporting said chain cutting mechanism in position to form adjacent unobstructed core openings, means for operating said cutting mechanism to cut an E-shaped kerf in a mine wall and form adjacent cores bounded by such kerfs and the face of the mine wall, and framework for supporting the aforesaid structure in position for operation on material in its native bed.

90. In a mining machine, the combination with a supporting frame, of a supplemental frame rotatively mounted thereon for pivotal movement on an upright axis, a multiple core cutter having adjacent unobstructed core openings therethrough, said cutter being mounted on said supplemental frame to move bodily therewith, and means for operating said multiple core cutter including swinging feeding movement on such upright axis to produce adjacent cores respectively extending through said unobstructed core openings.

91. In a mining machine, the combination with a supporting frame pivotally mounted for swinging movement on an upright axis, of a plurality of spaced apart kerf cutters comprising intermediate and outer kerf cutters mounted on said frame to swing bodily therewith, a plurality of spaced apart additional kerf cutters mounted on said supporting frame in a predetermined relation to said spaced apart kerf cutters to cooperate therewith to cut adjacent cores of material, and means for simultaneously operating said first-named spaced apart kerf cutters and said additional kerf cutters including swinging feeding movement on such upright axis to cut such adjacent cores.

92. In a mining machine, the combination with supporting framework, of a multiple core cutter having closely adjacent unobstructed core openings extending therethrough, means for operating said multiple core cutter to cut three spaced apart kerfs extending into the mine wall from the face thereof and communicating back kerfs spaced back from the face of the mine wall to produce closely adjacent cores extending through the respective core openings, and means for adjusting rectilinearly the height of said multiple core cutter relatively to said framework to vary its position of operation.

93. In a mining machine, the combination with supporting framework pivotally supported for swinging movement on an upright axis, of spaced apart plane kerf cutters mounted on said framework, an intermediate plane kerf cutter, additional kerf cutters for spanning the spaces between the intermediate kerf cutter and the outer kerf cutters, and means for operating all of said kerf cutters including feeding thereof by swinging said frame on said axis to effect the cutting of adjacent cores with the kerf formed by the intermediate kerf cutter the division between the cores.

94. In a mining machine, the combination with multiple core cutting mechanism having immediately adjacent unobstructed core openings therethrough, of means for driving said cutting mechanism, framework for supporting said core cutting mechanism for swinging feeding movement confined to an upright axis and means for feeding said cutting mechanism to cut closely adjacent cores by a single operation across the mine wall.

95. In a mining machine, the combination with a core-cutter having an unobstructed core-opening therethrough, of a supporting frame, means for mounting said core-cutter on said supporting frame for bodily rectilinear adjustment up and down relatively to said supporting frame and for cutting a core along the mine wall extending parallel to the length of the machine, and means for operating the core-cutter at its adjusted elevation to cut a core extending away from said supporting frame.

96. In a mining machine, the combination with loop chain core-cutting mechanism having an upper run straight in elevation and a lower run straight in elevation, of means for operating said loop chain core-cutting mechanism including the feed thereof, and means for adjusting the positions of said upper and lower runs to effect the cutting of the roof in a substantially horizontal plane and simultaneously the cutting of the floor in a substantially horizontal plane.

97. In a mining machine, the combination with a supporting frame, of loop chain core-cutting mechanism mounted thereon having upper and lower runs adapted to cut kerfs in spaced-apart parallel planes extending in the direction of the mine vein, and means for independently adjusting the elevation of said upper and lower runs in accordance with the lines of cleavage above and below the mine vein.

98. In a mining machine, the combination with a plurality of spaced-apart kerf-cutters, of a core-cutter for cutting a connecting kerf between the kerfs produced by said spaced-apart kerf-cutters, said connecting kerf being spaced back from the mine wall and substantially parallel thereto, means for adjusting the spacing between said first-named kerf-

cutters, and means for operating said kerf-cutters and said core-cutter including the feed thereof to effect the cutting of a core of material in its native bed.

5 In testimony whereof I have signed my name to this specification, on this 3rd day of February A. D. 1916.

EDMUND C. MORGAN.
